UNITED STATES PATENT OFFICE.

FRANCOIS DEBOVE, OF VILLE D'AVRAY, FRANCE.

CORK.

1,234,093.

Specification of Letters Patent. Patented July 17, 1917.

Application filed January 13, 1914. Serial No. 811,931.

To all whom it may concern:

Be it known that I, FRANCOIS DEBOVE, a citizen of the Republic of France, and a resident of Ville d'Avray, Department of 5 Seine and Oise, France, have invented a new and useful Cork, of which the following is a specification.

As is known it is customary to bleach cork stoppers or plugs before use, for example, 10 by dipping them in an aqueous solution of chlorid of lime.

Corks bleached by means of chlorid of lime present however the disadvantage of affecting the liquids with which they are 15 placed in contact. Moreover they are readily attacked by these liquids, to which they communicate the taste of the cork. Lastly it is necessary to allow them to dry before use, which operation involves a consumption 20 of heat and a loss of time.

The present invention relates to an improved cork in which the disadvantages referred to are avoided by subjecting the cork to a novel process of treatment.

25 This process consists in stirring or shaking up the corks with talc powder. The talc powder imparts to the corks a polished and silky surface which facilitates corking and in particular allows of dry-corking. On 30 the other hand the talc closes the pores of the corks and therefore increases their impermeability. Experience has shown that corks treated in accordance with the invention never communicate the taste of the 35 cork to the liquids with which they are placed in contact.

The talc may be colored for example with fuchsin, red ocher, brown ocher or yellow ocher, or anilin colors. For this purpose 40 there is prepared in alcoholic solution of gum to which the coloring material is added, the whole being then mixed with the talc powder, stirred and allowed to dry.

The carrying out of the process may take 45 place in a very simple manner by vigorously shaking up the corks mixed with the talc powder in a closed vessel; the corks are then placed in a muslin bag and again shaken up to free them from the excess of talc.

The apparatus shown on the annexed drawing may also with advantage be employed.

50 Figure 1 is a longitudinal section of the apparatus (a broken section on line 1—1 of Fig. 2);

Fig. 2 is a transverse section on line 2—2 of Fig. 1, seen from the left, and Fig. 3 is a side elevation partially in section showing a cork of the type to which my invention 60 relates.

The apparatus according to the invention consists of a case or chest A provided with a lid a movable upon a hinge a'. The chest A carries two bearings a² in which is journaled the shaft b of a rectangular drum B. Two faces of the drum B are closed by detachable solid shutters b' provided with handles b² and bolts b³. These shutters may be replaced by gauze-panels or sieves of the 70 same shape and size.

The rotation of the drum B is effected by means of pulleys b⁴ mounted at one end of the shaft b. The other end of the shaft carries a grooved pulley b⁵ which operates 75 through a belt c a revolution counter C having an alarm or bell.

Below the drum B is arranged an inclined sieve D movable around a hinge d. The higher edge of the sieve D rests normally 80 upon the cleats d' secured on the chest A; it is provided with a flange d² to which is attached a cord e which passes over guide pulleys e' and is connected to a handle e² placed outside. 85

Below the sieve D is arranged in the bottom of the chest A a sliding drawer f.

The chest A is provided with doors a³ which permit access to the sieve D.

The working of the apparatus is as follows:—The corks are filled into the drum B with a suitable quantity of talc; the shutters b' are replaced and the drum is revolved for the time necessary to impregnate the corks with talc. The drum is then 95 stopped; the shutters b' are removed and replaced by the sieves or gauzes, and the drum B is again set in rotation. The excess of talc passes through the sieves of the drum and through the sieve D into the drawer f 100 where it is collected. When the corks are freed from their excess of talc, the sieve is removed from the drum; the corks fall upon the sieve D. They pass out when the door a³ placed at the bottom of the sieve D is 105 opened. The handle e² and cord e allow of imparting to the sieve the shaking necessary to make the corks drop if they happen to remain caught in the meshes of the sieve.

110 Experience has shown that corks treated in accordance with the process of the invention are more impermeable than corks

treated by the ordinary processes and that therefore they never communicate the taste of the cork to the liquids with which they are placed in contact.

5 What I claim is:

1. As a new article of manufacture, a one-piece cork cut from the bark and having its surface impregnated and its pores closed with talc powder.

10 2. As a new article of manufacture a one-

piece cork cut from the bark, having its surface pores closed with a dry mixture of gum and talc.

In testimony whereof I have signed my name to this specification in the presence of 15 two subscribing witnesses.

FRANCOIS DEBOVE.
